US00D342237S

United States Patent [19]

Sharp

[11] Patent Number: Des. 342,237

[45] Date of Patent: ** Dec. 14, 1993

[54] **STORAGE SUBSYSTEM FOR A DATA PROCESSING SYSTEM**

[75] Inventor: **Michael H. Sharp**, Winchester, United Kingdom

[73] Assignee: **International Business Machines Corporation**, Armonk, N.Y.

[**] Term: **14 Years**

[21] Appl. No.: **757,436**

[22] Filed: **Sep. 9, 1991**

[30] **Foreign Application Priority Data**

Mar. 11, 1991 [GB] United Kingdom 2013505

[52] U.S. Cl. **D14/100**

[58] Field of Search D14/100, 102, 108, 109, D13/162, 184, 199; 360/99.12; 361/390-395

[57] **CLAIM**

The ornamental design for a storage subsystem for a data processing system, as shown and described.

DESCRIPTION

FIG. 1 is a top, front, right side perspective view for a storage subsystem for a data processing system showing my new design;

FIG. 2 is a front elevation thereof;

FIG. 3 is a rear elevation thereof;

FIG. 4 is a right side elevation thereof;

FIG. 5 is a left side elevation thereof;

FIG. 6 is a top plan thereof; and,

FIG. 7 is a bottom plan thereof.

FIG. I

FIG. 2

FIG. 3

FIG. 4

FIG. 5

FIG. 6

FIG. 7
